[57] CLAIM

The ornamental design for a shower stall or the like, as shown and described.

DESCRIPTION

FIG. 1 is a right front perspective view of a shower stall or the like showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a sectional view taken on lines 7—7 of FIG. 1;

FIG. 8 is a right front perspective view of a second embodiment thereof;

FIG. 9 is a sectional view thereof taken on line 9—9 of FIG. 8;

FIG. 10 is a right front perspective view of a third embodiment thereof.

The fragmentary broken line representation of a bathroom wall in FIGS. 1, 8 and 10 is for illustrative purposes only and forms no part of the claimed design.

FIG. 1

FIG. 2
